APPLICATOR

Stephen Malko, Chicago, Ill., assignor to Malko & Lock Machine Products, Chicago, Ill., a partnership composed of Stephen Malko and John A. Lock

Application November 12, 1946, Serial No. 709,143

3 Claims. (Cl. 128—185)

1

This invention relates to improvements in pressure applicators for medicaments or the like and more particularly to nasal syringes with which medicated air may be forced into the nasal passages and sinuses.

The heretofore used syringes, nasal douches, etc., as a general rule, directed a liquid into the nasal passages. This process was generally undesirable and unsuccessful as the nasal passages, when affected by hay fever, colds, and sinus infections were at least partly filled with a fluid or mucous which prevented the effective induction of any additional fluid. Because of this difficulty, it was desirable to induce medicated air into the affected channels. Induction of the air was usually accomplished by having the person so affected breathe or inhale the medicated air. Inhalation of medicated air proved undesirable as it was almost always impossible (due to the cold, etc.) to induct enough air into the affected channels to be effective. It was to overcome these and other obvious defects that the present invention was conceived.

The main objects of this invention are to provide a device of this character adapted to size and form, to be held in the hand and having one end thereof partially insertable into a nostril; to provide a device of this character which when operated manually will force medicated air into the sinus and nasal passages; to provide a device of this character which is manually operated by means of a piston; to provide a device of this character having an absorbent material in the discharge end capable of being saturated with a medicament and which is readily replaceable and removable; to provide a device of this character compact enough to be carried in a vest pocket or other small compartment; to provide a device of this character which is easily sterilized; and to provide a device of this character which is relatively inexpensive and simple to manufacture.

An illustrative embodiment of this invention is shown in the accompanying drawings in which:

Figure 1 is a side elevational view of the invention.

Fig. 2 is a cross-sectional view taken on line 2—2 of Fig. 1.

Fig. 3 is a top view of the device.

Fig. 4 is a bottom view thereof.

Fig. 5 is a sectional view taken on line 5—5 of Fig. 2.

Referring in detail to the drawings, the applicator which is preferably constructed of chrome-plated metal parts, comprises a cylindrical bar-

2

rel or body 1, the ends 2 and 3 of which are both open and are provided with internal threads. Piston 4 fits snugly within the body 1 and is adapted to be reciprocated therein. The piston is provided with an axially threaded bore 5 in the lower end thereof for the reception of a plunger which is adapted to seat in the bore 5 axially. The rod 6 is held axially in said housing by a guide bushing 8 which is threaded into the lower end 2 of the body 1. The bushing 8 is also provided with knurling 9 whereby to facilitate removal thereof when desired.

The body 1 is also provided with a hollow cap 10 having external threads 11 thereon adapted to be secured to the end 3. The cap 10 is provided with large axial bore or chamber 11.1 in the lower end thereof and a smaller internally threaded axial aperture 12 in the upper end thereof communicating with the bore 11.1. The finger gripping means comprises a washer-like disc 13 which is adapted to loosely seat in an annular groove 14 located in the cap 10, and a pair of bent arms 15 and 16 integrally formed on said disc 13 and each positioned laterally of said disc on opposite edge thereof.

A fine wire mesh screen 17 substantially equal in diameter to the inside diameter of the barrel 1 is adapted to fit snugly within the body 1 and is kept in tight abutment against the lower end 30 of the cap 10 by one end of a coil spring 18. The opposite end of the spring 18 abuts against and seats on the upper end of the piston 4 whereby when the piston is forced inwardly (or upwardly as viewed in Fig. 2) the spring 18 will cause the piston to return to the position shown in Fig. 2.

A domed-shape snout or nozzle 19 is provided with an externally threaded neck 20, which neck 20 is smaller in diameter than the main body of the nozzle 19 whereby to form a seat 20.1 which 40 is adapted to abut against the upper surface of cap 10 when threaded into the aperture 12 of the cap 10. A relatively large axial bore or chamber 21 extends substantially throughout the length of the nozzle 19 and communicates with the atmosphere through a relatively small air passageway 22, axially positioned in the top or dome end of the nozzle 19.

An absorbent material such as cotton, or the like, 23, saturated with a liquid inhalant, medicament, or the like, is placed in the chamber 11.1. Although I have shown saturated cotton as the preferred embodiment of my invention, it is to be understood that any medicament in solid or brick form may be used so long as the solid medicament 55 has an air passage or vent therein, whereby air

pressure developed in the upper end of the housing 1 by reciprocation of the piston 4 can readily pass therethrough or therearound and pass into the chamber 21 and out through the passage 22.

In operation the cap 10 is removed from the housing 1 and cotton 23 saturated with a medicament is placed in the chamber 11.1 of the cap 10. The cap is then replaced on the housing 1. The free end of the nozzle 19 is then inserted into one nostril and held in position by means of the finger grips. The piston 4 will, due to the action of the coil spring 18, be in the position shown in Fig. 2. The piston rod 6 is then quickly forced upwardly by the user's thumb thereby moving the piston 4 upwardly causing the air in the housing 1 to become under pressure due to the restricted outlet opening 22. The air under pressure passes through the wire screen 17 and into the chamber 11.1 through the saturated cotton 23 contained therein, into the chamber 21 and out through the passageway 22. The air forced past the cotton 23 picks up fumes only from the medicated cotton and thus medicated air is forced into the nasal passages. It is to be distinctly understood that medicated air only, and not a mist, or a fluid, is forced into the nasal passages by the use of the device of this invention.

It is to be understood that numerous details of this invention may be altered or omitted without departing from the spirit of this invention as defined by the following claims.

I claim:

1. In an applicator for forcing air into nasal passages an open-ended cylinder having internal threads at each end thereof, a piston in said cylinder, a piston rod removably secured to said piston and extending beyond one end of said cylinder, an externally threaded cap, an externally threaded bushing, said cap and bushing each having an axial aperture therein threaded one into each end of said cylinder, said rod being positioned in said bushing, a finger grip loosely anchored to said cap, a nozzle removably secured to said cap and having a chamber therein and an air port therein communicating with said chamber, a screen in the forward end of said cylinder, a coil spring interposed between said screen and said piston for normally urging said piston away from said screen, said cap having a chamber therein and medicated cotton in the chamber of said cap whereby medicated air under pressure may be

emitted from said port upon operation of said piston.

2. In an applicator for forcing air into nasal passages an open-ended cylinder having internal threads at each end thereof, a piston in said cylinder, a piston rod removably secured to said piston and extending beyond one end of said cylinder, an externally threaded cap, an externally threaded bushing, said cap and bushing each having an axial aperture therein threaded one into each end of said cylinder, said rod being positioned in said bushing, a nozzle removably secured to said cap and having a chamber therein and an exhaust port therein communicating with said chamber, a screen in the forward end of said cylinder, a coil spring interposed between said screen and said piston for normally urging said piston away from said screen, said cap having a chamber therein and medicated cotton in the chamber of said cap whereby medicated air under pressure may be emitted from said port upon operation of said piston.

3. In an applicator for forcing air into nasal passages an open-ended cylinder having internal threads at each end thereof, a piston in said cylinder, a piston rod removably secured to said piston and extending beyond one end of said cylinder, an externally threaded cap, an externally threaded bushing, said cap and bushing each having an axial aperture therein threaded one into each end of said cylinder, said rod being positioned in said bushing, a finger grip loosely anchored to said cap, a nozzle removably secured to said cap and having a chamber therein and an air port therein communicating with said chamber, a screen in the forward end of said cylinder, a coil spring interposed between said screen and said piston for normally urging said piston away from said screen, and a porous medicated material positioned in said cylinder between said port and said piston, whereby medicated air under pressure may be emitted from said port upon operation of said cylinder.
